United States Patent Office.

JOHN H. HUNTER, OF VERSAILLES, INDIANA.

Letters Patent No. 96,436, dated November 2, 1869.

IMPROVEMENT IN GATES.

The Schedule referred to in these Letters Patent and making part of the same.

To all whom it may concern:

Be it known that I, JOHN H. HUNTER, of Versailles, in the county of Ripley, and State of Indiana, have invented a new and useful Improvement in Gates; and I do hereby declare the following to be a full and correct description of the same, sufficient to enable others to understand and construct it, reference being had to the accompanying drawings, which make part of this specification, and in which—

Figure 1 is a plan of my improved gate;

Figure 2 is a side elevation; and

Figure 3, a perspective view of the same.

Like letters of reference indicate like parts in the several figures.

My invention relates to that class of gates which is opened from a carriage or horse, by means of levers secured to posts at a short distance from the gate-post; and

It consists in a peculiar combination and arrangement of levers, by means of which the gate is not only operated, but also locked and unlocked.

In the drawings, A A' represent the two posts, on opposite sides of a road, between which the gate B swings, being hinged to post A.

This gate is provided with a sliding bolt or latch, b, which catches in a recess in post A' to lock the gate.

Pivoted in a slot, c, in bolt b, is a short lever, a, the other end of which is connected to the longer arm of a bell-crank lever, C, pivoted to post A, and connected with its other and shorter arm to bars D D'.

These bars D D' are in a suitable manner pivoted to hand-levers E E', which in turn are pivoted to posts F F', these posts being in line with each other and post A.

Supposing a carriage to come toward gate B (which is closed) in the direction from post F, by pulling the

lever E in the direction of the arrow in fig. 3, the bar D operates on the shorter arm of bell-crank lever C, pushing it toward the post A, and moving the longer arm of the same away from the gate.

In this movement of this longer arm the short lever a takes part, operating bolt b, which, drawing out of the recess in post A', unlocks the gate.

When the lever a and the longer arm of lever C are nearly at right angles, the arm still moving away from the gate, this latter is forced to follow the lever a, the relative position of which to the longer arm of lever C remains unchanged until the gate strikes the little stop d, when its motion is arrested, while, the movement of the bell-crank lever still continuing for a moment, this motion is exerted upon bolt b, forcing it into a proper recess in post F, and locking the gate in position, as shown in red lines in fig. 1.

When the carriage has passed, and it is desired to put the gate again across the road, the lever E having moved to a position parallel to lever E, is moved in the direction of the blue arrow, fig. 3, when the above-described operation is reversed.

It will be easily understood that the same result is attained by operating lever E' in the direction of the red arrow, fig. 3, the bar D', in that case, pulling instead of pushing lever C.

Having thus described my invention,

What I claim as new, and desire to secure by Letters Patent, is—

The combination and arrangement of levers E E', C, a, bars D D', bolt b, and gate B, arranged to operate as herein described and shown.

JOHN H. HUNTER.
